CLAIM

The ornamental design for an arm warmer garment, substantially as shown and described.

DESCRIPTION

FIG. 1 is a front perspective view of an arm warmer garment showing my new design; the body shown in broken lines is for illustrative purposes only;

FIG. 2 is a front elevational view thereof;

FIG. 3 is a left side elevational view thereof;

FIG. 4 is a top plan view thereof;

FIG. 5 is a right side elevational view thereof; and

FIG. 6 is a rear elevational view thereof.

FIG. 6

FIG. 4
